GAS PURIFICATION

Fredrick D. Schreiber, Dormont, Pa.

Application June 8, 1938, Serial No. 212,549

5 Claims. (Cl. 23—3)

This invention or discovery relates to gas purification; and it comprises a method of purifying fuel gases, such as coke oven gas and the like, wherein the acidic gaseous constituents such as 5 H_2S , HCN and CO_2 are removed from a stream of the fuel gas and are then separated and utilized, advantageously by converting the H_2S into sulfuric acid and converting the HCN into a salable cyanide; and it comprises a new and useful combination of steps for effecting this result, and apparatus for use therein; all as more fully herein-after set forth and claimed.

Various methods have been proposed in the past for purifying coke oven gas and the like to eliminate the acidic constituents, and especially the H_2S , therefrom. Some of these methods have met with considerable commercial success. Recently, the hot actification processes of purifying gases, including refinery gas and natural gas as well as coke oven gas, have found commercial favor; and these processes have the outstanding advantage that H_2S is recoverable in concentrated form, so that it may be easily burned to sulfur dioxide and used as a raw material in the production of sulfuric acid. This is often economical, because most refineries, coke oven plants, etc., in which it is desirable to remove H_2S from gases, also consume substantial quantities of sulfuric acid. A process making it possible to convert the heretofore undesirable H_2S into useful sulfuric acid is therefore highly advantageous. Useful embodiments of the hot actification process are described in U. S. Patents 1,971,798, 2,028,124, and 2,028,125, for example.

Various methods have also been proposed heretofore for recovering another acidic constituent, the cyanogen or HCN , which is found especially in coke oven gas. Some of these methods have been found commercially satisfactory, and have been used in conjunction with various methods of removing the other acidic constituents, and especially the H_2S , from coke oven gas and the like. To the best of my knowledge, however, no commercially acceptable method has heretofore been proposed for recovering HCN from coke oven gas, etc., simultaneously with the removal of H_2S by a hot actification process, such as the sodium phenolate process. An object achieved by my present invention is to remove the H_2S and HCN from coke oven gas, for example, by a hot actification process such as the sodium phenolate process, and to economically recover the H_2S and HCN separately, in salable or usable form. One of the advantages of my invention is that this re-

sult is achieved in a simple and economical manner.

In accordance with my invention as applied to coke oven gas, the gas from the coke oven battery is first passed through primary coolers and separators for pitch and tar in the usual manner, and is then passed through a sulfuric acid saturator, to remove the ammonia contained therein. Generally, vapors from the ammonia still, containing the ammonia and the acid gases (including H_2S and HCN) contained in the various condensates produced during the treatment of the gas, are combined with the gas stream entering the saturator. Substantially all of the ammonia formed or liberated by carbonizing coal in the coke ovens is thus recovered in the saturator in the form of ammonium sulfate, which is withdrawn from time to time or continuously for sale, in known manner.

The substantially ammonia-free gas ordinarily leaves the saturator at a temperature on the order of 50° to 60° C. and this gas is passed through a cooler, often designated a final cooler, in which its temperature is reduced to about 20° to 30° C. In this cooling stage, I find it advantageous to employ direct cooling with water maintained at the desired temperature, as the condensate formed from the gas during cooling then combines with the recirculated water. The excess water in the system is discharged from the cooling system to the ammonia still or the ammonia liquor storage tank, from which it is sent to the still. In either case, any ammonia or acidic constituents such as H_2S and HCN contained in the liquor are returned to the gas stream, and ultimately recovered.

The water circulated through the final cooler system is cooled in an indirect type of cooler suitably connected to the line returning water to the cooling tower, and maintains this water at the desired temperature. I find it advantageous to use an indirect cooler for maintaining the water temperature rather than an evaporative cooler, in order to prevent loss of H_2S or HCN from the system. Because of this precaution, substantially the entire H_2S and HCN contents of the gas are ultimately recovered.

The cooled gas leaving the final cooler at a temperature of the order of 20° to 30° C. enters an absorber constituting part of a hot actification gas purifying system, which preferably employs sodium phenolate as the absorbing solution. This absorber is advantageously of the two-section type, with actified solution supplied at an intermediate point above the first section

and more highly actified solution supplied to the top of the absorber above the second section. The absorbing solution is cooled before it is supplied to the absorber, and at the temperature of 5 the solution and the gas, the H_2S and other acidic gases, including HCN and CO_2 , are absorbed, liberating phenol from the phenolate. Most of 10 this absorption takes place in the first or lower section of the absorber. Some absorption of the acid gases takes place in the second section of the absorber, but the principal function of the second or upper section is to prevent loss of phenol 15 liberated in the lower section. The solution supplied to this second section is advantageously so highly actified that it is not saturated with respect to phenol, and will therefore have a capacity for picking up any phenol carried forward by the gas stream.

The gas leaving this absorber is purified with 20 respect to acidic constituents as well as ammonia, and may be discharged to the gas holder or distributing system, or passed through the light oil scrubbers if benzol recovery is to be practiced.

The highly actified absorbing solution of sodium phenolate supplied to the upper section of the absorber passes downwardly into the first or lower section of the absorber, where it assists in the absorption of acid constituents from a further quantity of gas. All of the solution containing 25 the absorbed acid constituents and the phenol liberated by their absorption is then passed through heat exchangers into the top of the actifier. There the acid gases are driven out by heat, which is ordinarily supplied by steam coils 30 adapted to heat the solution. To effect this actification, it is necessary to heat the solution substantially to the boiling point. This theoretically causes the phenol and its homologues, such as the cresols, to attain an acidity higher than that 35 of the previously absorbed H_2S , CO_2 and HCN, thus reversing the condition prevailing in the absorber. The absorbed acid gases are therefore liberated by reaction of their salts with the phenols. For example, sodium hydrogen sulfide 40 acts with phenol at this temperature to liberate H_2S , reforming sodium phenolate.

The solution being actified passes downwardly through the actifier tower, where its actification is continuously improved by the progressive 45 high temperature reaction. All of the solution may be passed down through the tower and recirculated through heat exchangers and coolers to a single step absorber, if desired. Ordinarily, however, it is advantageous to withdraw a substantial 50 proportion of the solution at an intermediate section of the actifier, and return this solution through suitable cooling devices to the first or lower section of the absorber. This solution is sufficiently actified to absorb most of the acidic 55 gases from the stream of fuel gas. The remainder of the solution is allowed to pass on down through the lower section of the actifier tower, where it becomes very highly actified due to the longer boiling. In fact, it is desirable to actify this part 60 of the solution so highly that it is slightly impoverished in phenol, and is thus able to pick up phenol in the second or upper portion of the absorber.

If desired, actifiers and absorbers having more 65 than two sections in each may be employed, but this greater complication is seldom, if ever, justified by the improvement in results obtained in commercial scale operation.

The H_2S , CO_2 and HCN liberated during actification pass out of the actifier, and are usually ac-

companied by water vapor and a certain amount of phenol. It is therefore advantageous to pass these effluent vapors through a dephlegmator maintained at such a temperature that substantially all of the water and phenol are condensed 5 and returned to the actifier. The gases leaving the dephlegmator then consist of about 70 per cent H_2S , 16 per cent CO_2 , and 13 per cent HCN, with ordinary operation and with the coals now generally employed for coking. In a plant 10 producing 20,000,000 cu. ft. of coke oven gas per day, there is discharged from the actifier dephlegmator between 9,000 and 10,000 cu. ft. of these mixed acid gases per hour.

My next step is to separate the HCN, which I 15 desire to recover, from the other acid gases, and I find that this is conveniently effected by compressing the gases and scrubbing them with cold water. Scrubbing with cold water under pressure effects a preferential absorption of the HCN, 20 and conditions of temperature, pressure and flow of water and gas may be readily adjusted so that all of the HCN is absorbed with relatively small amounts of H_2S and CO_2 . The gases which are not absorbed are discharged from this pressure 25 absorber, and may be forwarded to an acid plant where the H_2S is burned to SO_2 and converted into sulfuric acid in known manner. For example, the contact process may be satisfactorily employed with this gas. 30

The aqueous solution produced in the pressure absorber contains all of the HCN originally present in the coke oven gas, and some of the H_2S and CO_2 . This solution is pumped to another tower, where it is scrubbed with a counterflow of 35 purified gas withdrawn from the discharge line of the phenolate absorber, or from any other convenient source. A very small amount of this gas is sufficient, when properly contacted with the HCN solution, to eliminate all the H_2S and CO_2 40 from the solution. The purified gas containing this removed H_2S and CO_2 , and usually containing a small amount of HCN, is returned to the inlet of the phenolate absorber, so that none of these acid gases is lost from the system. If desired, a part of the HCN solution discharged from the pressure absorber may be recirculated through part or all of this absorber to increase its concentration before scrubbing it with the purified coke oven gas. 50

After scrubbing with the purified coke oven gas, the aqueous solution contains substantially only HCN, which is liberated in any convenient manner. One method which I have found to be especially simple and effective is to slightly acidify 55 the solution with a stronger acid, such as H_2SO_4 , while maintaining the solution under a vacuum. This may be advantageously effected by discharging the solution to a closed tower or vat, to which a small amount of H_2SO_4 is supplied while agitating the solution, and maintaining it under a vacuum by connecting it with the intake of a vacuum pump. This completely removes the HCN from the solution, and the dilute acidified water may then be discharged to waste or for utilization. 60

The gaseous HCN withdrawn by the vacuum pump from the solution is readily converted into any of several cyanogen compounds which find a ready market. If sodium cyanide, for example, is to be produced, the HCN gas need only be bubbled through a suitable solution of caustic soda. This may be done in any suitable device, but I find it convenient to employ a closed tower through which the caustic solution and the gaseous HCN are passed in counterflow. The outlet 65

from the vacuum pump may, for example, discharge into the bottom of such a tower, and any gas unabsorbed during a single passage through the tower may be returned to the intake of the pump through a suitable conduit. The solution may also be recirculated through the tower if desired, to complete the conversion of NaOH to NaCN. The NaCN solution is continuously removed from the tower or from a circulation sump, 10 and may be further concentrated by evaporation, or otherwise worked up if desired.

In order that my invention may be more readily understood and appreciated, it will now be described briefly with a reference to the 15 accompanying drawing, which is a flow-sheet setting forth the essential parts of the process. In the flow-sheet, 2 indicates a saturator of conventional type, to which sulfuric acid is supplied through an inlet 4. Coke oven gas or the like 20 is introduced into the saturator through a pipe 6, into which the ammonia still vapors are ordinarily discharged from a pipe 8. The ammonia in the gas reacts with the H₂SO₄ to form ammonium sulfate, which is withdrawn from the 25 saturator either continuously or from time to time through an outlet 10.

The ammonia-free gas is discharged from the saturator through a pipe 12, from which it passes into the bottom of a cooler 14, containing suitable packing 16, which facilitates contact between the gas and the cooling water. After cooling the gas, water containing constituents removed therefrom and condensate formed by cooling is discharged from the bottom of the cooler 30 through a pipe 18 to a sump 20. As the amount of liquid in the system builds up, due to condensation from the gas, excess liquid is withdrawn through an overflow line 22, and sent to the ammonia still or the ammonia liquor storage tank (not shown). Cooling water is withdrawn from the sump 20 by a pump 24, and returned through a cooler 26 of the indirect type, and pipe 28, to the top of the final cooler 14, through which it flows downwardly, cooling a 40 further quantity of gas. The indirect cooler 26 for the circulating water is provided with the customary inlet and outlet for cooling water. When starting up the system, or at other times when needed, water may be introduced through 45 the pipe 27.

The cooled gas leaving the top of the final cooler 14 passes through a pipe 30 into the bottom of an absorber 32 for acidic gases. The absorber illustrated is of the two-section type, 55 having a lower section 34 and an upper section 36. Highly actified solution of sodium phenolate is supplied to the top of the upper section 36 of the absorber through a pipe 38, and passes downwardly through said upper section and into the lower section 34. In the lower section, it combines with a further quantity of actified solution supplied through the pipe 40, and the combined solution removes the acidic constituents from the gas. Purified gas is discharged from 60 the absorber through an outlet pipe 42 to the benzol scrubbers or the gas distributing system.

The phenolate solution containing absorbed H₂S, HCN and CO₂ is collected in a suitable sump or storage tank 44 at the bottom of the absorber, 70 from which it is delivered by a pump 46 through a heat exchanger 48 and a pipe 50 to the top of an actifier 52. In this actifier, the solution is heated by steam, which may suitably be supplied to coils 54 at the bottom of the actifier tower, and the H₂S, CO₂ and HCN are driven out of the

solution as previously described, passing from the actifier through a pipe 56 to a dephlegmator 58, which condenses and returns to the actifier any water and phenol carried out with the acid gases. The HCN, H₂S and CO₂ then pass on 5 through a pipe 60 for further treatment.

Partially or substantially completely actified solution may be withdrawn from an intermediate portion of the actifier through a pipe 62, and returned as by pump 64 through pipe 66, 10 and the heat exchanger 48 to a pipe 68, and a cooler 70 and pipe 72 into pipe 40, which discharges it into the lower section of the absorber 32. The remainder of the solution passes downwardly through the actifier, and is discharged 15 through pipe 74 and pump 76, which delivers the highly actified solution through a pipe 78 to the heat exchanger 48, or another heat exchanger, then through a pipe 80 and a cooler 82 into pipe 84, which returns it to the top of the absorber. 20 In the absorber, this solution takes up phenol vapors and acidic gases, as previously described.

The acidic gases discharged from the dephlegmator 58 through the pipe 60 are compressed as by a compressor 84, which discharges them into 25 a scrubber 86, to which cold water is supplied, as by a pipe 88. The conditions of temperature and pressure are so maintained that all of the HCN and a minimum of H₂S and CO₂ are absorbed in the water. The H₂S and CO₂ which 30 are not absorbed, are discharged from the scrubber through a pipe 90, by which they may be delivered to a sulfuric acid plant or other point of disposal.

The aqueous liquid containing the HCN and 35 other gases absorbed in the pressure scrubber 86 is withdrawn by a pump 92 and delivered through a pipe 94 to another scrubber 96, although part of this solution may be recirculated or by-passed from pipe 94 through a pipe 98 into the pressure 40 scrubber 86, if desired. In the scrubber 96, the HCN solution containing CO₂ and H₂S is scrubbed, preferably by a counterflow of purified coke oven gas which may conveniently be withdrawn from the purified gas line 42 through a 45 pipe 100 by the blower 102, and delivered into the bottom of this scrubber 96. The gas passing through the solution may be readily controlled to eliminate all the H₂S and CO₂ from the solution, usually taking with it a small proportion 50 of the HCN. This gas is discharged from the scrubber 96 through a pipe 104, and may conveniently be returned to the pipe 30, and thence to the absorber 32, where the acid gases are again taken up and the purified gas is sent forward. 55 There is thus no loss of acid gases from the system.

The purified HCN solution is withdrawn from the bottom of scrubber 96 through a pipe 106 by a pump 108, which delivers it through a pipe 110 60 to another container 112, where the HCN is liberated by a stronger acid such as H₂SO₄ supplied through a pipe 114. Upon mixture with the acid, the HCN is readily liberated from the solution, and is withdrawn from the tank 112 through a pipe 116, connected to the intake of a vacuum pump 118. The acidified solution free of HCN is 65 discharged from tank 112 through an outlet 120, for any desired disposal.

The gaseous HCN is delivered by the vacuum 70 pump 118 to a reaction tank 122, where it is converted into any desired composition. This reaction vessel 122 may conveniently take the form of a relatively tall tower to which caustic soda solution is supplied near the top through a pipe 124. 75

The caustic solution flows downwardly through the tower, reacting with the HCN to form NaCN in solution, and any of the HCN which is not absorbed may be discharged from the tower 5 through a pipe 126, and returned to the inlet of the vacuum pump 118, and thus recirculated until it is absorbed. The sodium cyanide solution is withdrawn from the tower through a pipe 128, and may be worked up into some other compound, 10 or concentrated by evaporation, or recirculated through pipe 124 if desired.

It is thus a simple and economical matter, in accordance with my invention, to recover separately, for utilization or other disposal, substantially the entire amount of acidic gases present in coke oven gas and the like. Optimum conditions for maximum recovery and separation of the acidic gases vary somewhat with the nature of the original gas, and with the original proportions of 20 the acidic constituents therein. In general, however, satisfactory results are obtained by scrubbing the mixture of H₂S, HCN and CO₂ at a pressure of 50 to 100 pounds per square inch. This forms a solution in which the ratio of HCN to the other gases is much higher than in the gas from the actifier. The purified coke oven gas or other inert gas employed to remove the H₂S and CO₂ from this solution need only be sufficient to give a concentration of about 600 to 700 grains 30 of H₂S per 100 cubic feet in the gas discharged from this tower to an earlier stage in the system. The cyanide solution remaining after this treatment may advantageously have a concentration of about 1 to 2 per cent of HCN. It should be 35 understood, however, that these data are given by way of illustration only, and not by way of limitation.

What I claim is:

1. The method of recovering HCN from a mixture of acidic gases constituting the effluent from the actifier of a hot-actification gas purifying system, said mixture containing H₂S as a principal constituent and a smaller quantity of HCN, and said purifying system including an absorber in which the said acidic gases are removed from coke oven gas, which comprises scrubbing the acidic gaseous effluent from said actifier with water under conditions of temperature and pressure which favor the absorption of HCN and thus obtaining an aqueous solution containing substantially all the HCN in said gaseous mixture, contacting said solution with a flow of coke oven gas purified from acidic constituents in the said absorber and thereby removing from the solution

absorbed constituents of said gaseous mixture other than HCN, returning the said gas to the said absorber with the constituents which it removes from said aqueous solution of HCN, and recovering HCN from the solution. 5

2. The method of purifying coke oven gas, which comprises removing ammonia from the gas, cooling the substantially ammonia-free gas, absorbing acidic constituents including H₂S and HCN from the cooled gas with a solution comprising sodium phenolate, recirculating the sodium phenolate solution through an actifying stage wherein it is heated to drive off said acidic constituents and a stage wherein it is cooled and the absorbing stage wherein said acidic constituents are removed from gas thereby, withdrawing from said actifying stage a mixture of acidic gases including H₂S and HCN removed from the coke oven gas in said absorbing stage, contacting said mixture of acidic gases with water to form a 20 solution containing substantially all of the HCN and some of the other acidic gases of said mixture, contacting said solution with a stream of purified coke oven gas freed from acidic constituents in said absorbing stage to remove said other 25 acidic gases from the solution and thus preparing a substantially pure aqueous solution of HCN, returning the resulting mixture of coke oven gas and acidic gases to the said absorbing stage for separation of the acidic gases therefrom, and 30 recovering substantially pure HCN from said aqueous solution thereof.

3. The method of claim 2, wherein said cooling of the ammonia-free gas is effected by direct contact with cooling water, and wherein said cooling 35 water is recirculated through a stream of said gas and through a stage in which it is cooled without loss of constituents absorbed from said gas.

4. The method of claim 2, wherein said cooling 40 of the ammonia-free gas is effected by direct contact with recirculated cooling water, and wherein condensate formed from the gas is withdrawn from the recirculatory cooling water system and distilled and gaseous constituents thereof are returned to a stream of said coke oven gas for recovery thereof. 45

5. The method of claim 2, wherein said mixture of acidic gases is compressed and scrubbed with cold water to form said solution containing substantially all of the HCN removed from the said coke oven gas. 50
